REFRIGERATION

Curtis C. Coons, North Canton, Ohio, assignor to
 The Hoover Company, North Canton, Ohio, a
 corporation of Ohio

Application July 18, 1942, Serial No. 451,443

25 Claims. (Cl. 62—119.5)

This invention relates to the art of absorption refrigerating apparatuses and more particularly to an absorption refrigerating apparatus of the three-fluid type, especially adapted to produce a useful refrigerating effect at a first temperature level suitable for effective preservation of foodstuffs and the like and to produce a second refrigerating effect at a lower temperature level suitable for freezing ice, producing frozen foodstuffs and the like.

It is further a particular object of the present invention to provide low temperature refrigeration for the production of ice and the like by evaporating substantially pure liquid refrigerant into an inert gas and to provide for higher temperature refrigeration for the preservation of foodstuffs and the like by evaporating liquid refrigerant from a solution of the refrigerant and absorbing liquid into the inert gas.

It is a further object of the present invention to precool the pure liquid refrigerant being supplied to the low temperature refrigerating zone by passing the same in heat exchange relationship with refrigerant evaporating out of absorption solution into the inert gas.

It is a still further object of the present invention to promote economy of operation of apparatuses of the above described character by condensing the vapors discharged from the generating apparatus by passing such vapors in heat exchange relationship with the cold liquid produced in the high temperature evaporating zone and to produce the refrigerant utilized in the low temperature evaporating zone from the liquid discharged from the high temperature evaporating zone.

Other objects and advantages of the invention will become apparent as the description proceeds when taken in connection with the accompanying drawings in which:

Figure 1 is a diagrammatic illustration partly in section and partly in enlarged perspective of a refrigerating apparatus embodying the present invention.

Figure 2 is a partial sectional elevational view illustrating the manner in which the present invention is associated with the cabinet of a domestic refrigerating apparatus, and

Figure 3 is a view similar to Figure 1 of a modified form of the invention.

Referring now to Figure 1 there is illustrated a three-fluid absorption refrigerating apparatus comprising a boiler B, an analyzer D, a heat transfer element R designed to produce a very rich solution of refrigerant in the absorbent and also

to liberate substantially pure refrigerant vapor, a condenser C, a low temperature evaporator E, a high temperature evaporator H, a gas heat exchanger G, a tubular air cooled absorber A, a solution reservoir S, a liquid heat exchanger L, a circulating fan or pump F which is driven by a suitable electrical motor M. These elements are suitably interconnected by various conduits to form a plurality of gas and liquid circuits to be described hereinafter.

The above described system will be charged with a suitable refrigerant, such as ammonia, an absorbent therefor such as water and an inert pressure equalizing medium, preferably a dense inert gas such as nitrogen.

The boiler B will be heated by an electrical cartridge heater or by a combustible fuel burner such as a gas burner.

The heating element for the boiler and the electrical motor M will be governed by any suitable control mechanism for regulating the production of refrigeration. A preferred form of control mechanism is illustrated and described in United States Patent No. 2,228,343, issued January 14, 1941.

In the normal operation of the apparatus the application of heat to the boiler B causes the evolution of vapor of the refrigerant and vapor of the absorbent from the solution therein contained. The vapor so formed passes upwardly through the analyzer D in contact with and in counterflow relationship to strong absorbent solution flowing downwardly through the analyzer. The resulting vapors are then conveyed from the upper portion of the analyzer D through the conduit 11 to the inner path of the portion 12 of the heat exchange element R. A portion of the vapors supplied to the conduit 11 are condensed in the element 12 and are drained therefrom through the U-shaped conduit 13 into the inner path of the second portion 14 of the heat exchanger R wherein the condensate is pre-cooled in a manner to be described hereinafter. The condensate formed in the element R consists of absorption solution and liquid ammonia consisting, for example, of about 80% by weight of liquid ammonia.

The condensate formed in element 14 is conducted through the conduit 15 into the gas supply conduit 17 of the evaporator H through which it flows by gravity in counterflow relationship to the inert gas. Conduit 15 includes a U-shaped gas lift pump portion 15a to elevate the condensate into the evaporator which is higher than element R. Pumping gas is introduced into the evaporator leg of U-shaped element 15a by con-

duit 15b which connects to a gas conduit 35. Part of the ammonia content of this condensate evaporates in the evaporator H to produce a useful refrigerating effect and the remaining liquid is then drained by gravity from the gas discharge conduit 18 of the evaporator H by means of a conduit 20 into the outer path of the element 14. This cold liquid is heated in the element 14 and serves to cool the condensate enroute to the conduit 15. The liquid is then discharged through the conduit 21 to the outer path of the element 12 of the heat exchanger R in which it is brought into heat exchange relationship with the hot vapors supplied to the conduit 11.

In the element 12 refrigerant vapor is evolved from the rich solution discharged from the evaporator H. The refrigerant vapor then flows through conduit 23 to the condenser C. The remaining solution is then drained through the conduit 24 to the rich solution return line 25 of the boiler-analyzer assembly. The conduit 24 opens into the upper portion of the element 12 to insure that the inner conduit of the element 12 will always be submerged in the condensate.

A U-shaped finned conduit 26 is connected to the bight portion of the U-shaped conduit 13 in order to relieve the element R of vapor which has passed therethrough undischarged, and also to purge the element R of any non-condensable vapors. These vapors and non-condensable gases pass through conduit 26 to the condenser C. Any condensate formed in conduit 26 drains back into the conduit 13 and flows into the evaporator H.

The vapors supplied through conduit 23 are substantially pure ammonia and as a result the condensate formed in the condenser C is pure liquid ammonia. This condensate is drained from the bottom portion of the condenser through the conduit 27 to the gas inlet portion 28 of the freezing evaporator E. The conduit 27 is U-shaped to form a liquid sealing trap and passes in contact with the air cooling fins 29 on one section of the evaporator H in order to pre-cool the liquid refrigerant.

The evolution of refrigerant vapor in the boiler B produces a weak solution of refrigerant in the absorbent which is removed therefrom to the reservoir S by way of the conduit 30, liquid heat exchanger L, and the finned looped pre-cooling conduit 31. The liquid is conveyed from the reservoir S to the upper portion of the absorber through the gas lift pump conduit 33 which is supplied with pumping gas from conduit 34 which connects to the discharge conduit 35 of the inert gas circulator F. The upper gas space of the reservoir S is vented by means of the conduit 36 to the suction connection 37 of the circulating fan thereby placing the liquid in the reservoir S under the suction pressure of the fan which is the lowest pressure prevailing in the system.

The absorbing solution flows downwardly by gravity through the absorber A in counterflow relationship with and in contact with a rich mixture of inert gas and refrigerant vapor supplied to the absorber from the evaporator in a manner to be described hereinafter. The solution absorbs refrigerant vapor from the gas vapor mixture and the resulting enriched solution is conveyed from the bottom portion of the absorber to the analyzer D by way of the conduit 39, the liquid heat exchanger L, and the conduit 25.

A vent conduit 40 is connected between the vent conduit 36 of the reservoir S and the lower portion of the condenser C above the liquid level in the conduit 27 in order to relieve the condenser of

non-condensable products and to maintain the condenser pressure substantially at that prevailing in the suction conduit 37 of the gas circulator F.

The inert gas which is discharged under pressure from the circulating element F passes through the conduit 35, the inner path of the gas heat exchanger G and conduit 28 where it enters the evaporator E. The inert gas flows through the evaporator E with sufficient velocity and pressure to circulate the liquid refrigerant therethrough by the frictional drag of the relatively high velocity stream of inert gas flowing in contact therewith. Thus the inert gas serves to distribute the liquid and to circulate the same through the conduit forming the evaporator E as the liquid is evaporating into the inert gas to produce a refrigerating effect.

After traversing the evaporator E the inert gas exits therefrom through pipe 42 to the outer path of the gas heat exchanger from which it is conveyed through the conduit 18 into the evaporator H. The evaporator H is sloped downwardly from its point of connection with conduit 15a to provide for gravity flow of the refrigerant counter to the flow of the inert gas. The cross sectional area of the conduits forming evaporator H is larger than the cross sectional area of the conduits forming evaporator E. The solution partially evaporates in evaporator H and produces a refrigerating effect as described hereinabove. The inert gas is then conveyed from the gas discharge conduit 17 of the evaporator H to the bottom portion of the absorber A by means of the conduit 43. The inert gas then flows upwardly through the absorber A and returns to the gas circulator through the conduit 37.

Referring now to Figure 2 the manner in which the above described refrigerating apparatus is assembled with a cabinet will be described. Only the upper portion of the cabinet structure and its associated refrigerating elements are illustrated in detail as the arrangement of the mechanism compartment, particularly the arrangement of boiler, absorber, solution circuit conduits and the circulating fan and its motor will be substantially that illustrated and described in U. S. Letters Patent 2,250,944, issued July 29, 1941, that is, with the absorber, boiler assembly underlying the food storage chamber of the cabinet structure.

The cabinet structure 50 comprises an insulated housing 51 which contains in its upper portion an insulated partition 52 separating the housing into an upper freezing chamber 53 and a lower food storage chamber 54. The chambers 53 and 54 may be reached through the insulated cabinet door 55. An additional door 56 is provided for the chamber 53 in order to prevent warming of the freezing chamber when the door 55 is opened solely for the purpose of obtaining access to the chamber 54.

The evaporator E is positioned in the lower portion of the chamber 53 and supports on its upper surface a flat plate 57 of heat conducting material which is adapted to support freezing receptacles such as ice trays and the like.

The evaporator H which is provided with air cooling fins, as shown, is positioned in the upper portion of the chamber 54 directly beneath the partition 52.

The condenser C is positioned in the upper portion of an air flue 60 which extends vertically along the rear side wall of the cabinet 50 and in the usual manner will communicate with the un-

derlying mechanism chamber which is also open for flow of cooling air therethrough. The gas heat exchanger, the auxiliary condensing element 26, the parts 12 and 14 of the element R, the various connecting conduits are positioned in the flue 60 in the manner shown. If desired, insulating material may be applied to the gas heat exchanger G, the various portions of the element R and the conduit connecting the element R to the analyzer and to the evaporator H.

The rear wall of the cabinet 50 is provided with an opening 61 which is designed to be closed by an insulated closure or window element 62. A suitable gasket 63 may be provided to seal the joints between the cabinet and the element 62.

When the apparatus is constructed the entire refrigerating machine will be assembled together with the element 62 and will be tested as a unit after which the refrigerating apparatus will be slid forwardly into the cabinet from the rear to extend the evaporator elements through the opening 61 and to bring the element 62 into position in that opening.

The plate 52 as shown is formed integrally with the cabinet and is provided with a slot 64 which is sealed by a forwardly projecting panel 65 to accommodate the vertically extending portion of the conduit 27. However, if desired the panel 52 may be made as an integral part of the element 62 in which event it will be assembled with the cabinet when the refrigerating mechanism is assembled therewith.

Referring now to Figure 3 there is illustrated a modified form of the invention of the type in which the liquid refrigerant is circulated by a heat operated vapor lift pump and the circulation of inert gas is achieved by the density differential existing between the cold rich gas enroute to the absorber and the warm lean gas flowing from the absorber to the evaporator. With this form of the invention a light gas such as hydrogen is preferred as the pressure equalizing medium.

This form of the invention includes certain elements substantially identical in structure and function with elements previously described in detail in connection with Figure 1. These elements are therefore given the same reference characters as their counterparts in Figure 1 primed.

This form of the invention will be charged similarly to the form of the invention described above and the boiler B' will be provided with a suitable heating means which will be controlled in any desired manner.

The application of heat to the boiler B' generates refrigerant vapor from the strong solution therein contained and produces weak solution. The vapor so formed elevates the weak solution through the vapor lift conduit 80 by the well-known vapor lift action and the resulting lean solution flows through the conduit 81, liquid heat exchanger L' and conduit 82 to the upper end of the absorber A'. The rich solution formed in the absorber flows from the lower portion thereof to the boiler B' by way of the conduit 83, liquid heat exchanger L' and conduit 84, thus completing the absorbing solution circuit. The vapor lift conduit 80 discharges into a vapor separation and analyzing chamber 85, the vapor passing upwardly across the plates 86 forming the analyzer in contact with a rich solution of refrigerant and ammonia derived from a source to be described hereinafter. The hot vapor serves to evolve refrigerant vapor from this solution and the resulting vapors pass through the conduit 11'

into the element 12' of the element R', which functions similarly to the element R described above.

The inner pass 14' of the element R' is connected by conduit 91 to a gas separation vessel T. The vessel T is positioned with its lower portion at an elevation above the upper or gas outlet portion of evaporator H' and is drained into the upper portion of evaporator H' by means of a U-shaped conduit 93. The upper or gas containing space of vessel T is vented by conduit 92 which connects to the lower end of condenser 26'. The upper end of condenser 26' is vented by conduit 95 to the upper portion of condenser C'.

15 The condensate flows by gravity through evaporator H' and is drained from the lower gas inlet portion of evaporator H' by means of conduit 94. Conduit 94 opens into the outer pass of heat exchanger R'.

20 In operation the vapors supplied to the heat exchanger R' condense into the inner pass thereof until a gas seal is formed after which the boiler pressure increases substantially to force the accumulated condensate and some of the vapor upwardly into the vessel T after which the vapor flows into condenser 26' and is condensed except for non-condensable materials which pass on to the condenser C'.

25 The solution which passes through the element 12' after evolution of refrigerant vapor therefrom drains through the conduit 87 to the upper end of the analyzer gas separation chamber 85 and flows downwardly across the plates 86 in contact with and in counterflow relationship with the vapor flowing upwardly through the chamber 85 to the conduit 11'.

30 In this form of the invention the evaporator H' is identical in construction and function with the evaporator H described above.

35 40 In this form of the invention the ice freezing evaporator 89 is formed of a relatively large diameter conduit which is continuously sloped downward slightly from its point of connection with its gas discharge conduit 42' to its gas supply conduit 28' to provide for gravity flow of liquid refrigerant therethrough. The evaporator 89 supports a horizontal tray supporting shelf 100 which is secured to and maintained in horizontal position by channel element 101. the warm lean column of inert gas flowing upwardly through the conduit 90 and the cool rich column of inert gas descending through the conduit 43'.

This form of the invention is designed and intended to be assembled with a cabinet structure similarly to the manner in which the form of the invention illustrated in Figure 1 is associated with a cabinet structure.

The present invention is particularly designed and intended to provide satisfactory refrigeration at a low temperature freezing level and at a high temperature food preservation level while utilizing a three-fluid absorption refrigerating mechanism. This object is particularly accomplished by producing the high temperature refrigerating effect by evaporating from a solution of the liquid refrigerant in the absorbent containing approximately 80% by weight of refrigerant when supplied to the high temperature evaporating coil. By this means the high temperature refrigerating effect is efficiently produced and the evaporator will never frost up though it may collect some condensate when the air within the compartment 54 is humid. If desired, a suitable louvred condensate collecting tray may be positioned beneath the evaporators H and H'.

The present invention efficiently utilizes the necessary rectification of the vapors in refrigerating apparatuses to provide the refrigerant for the high temperature evaporating zone and at the same time insures that the heat of rectification will not be wasted and rejected ultimately from the system. This object is accomplished by utilizing the heat of rectification to produce substantially pure refrigerant vapor from the solution discharged from the high temperature evaporator. The vapor so produced is then condensed in an air-cooled condenser and is supplied to the low temperature evaporator. The high temperature evaporator operates on a solution of refrigerant in the absorbent and the low temperature evaporator operates with pure liquid refrigerant.

In the form of the invention illustrated in Figure 1, the overflow solution from the rectifying heat exchange element mixes with the rich solution returning to the analyzer and flows into the analyzer.

In the form of the invention illustrated in Figure 3 the solution discharging from the rectifying element forms the sole liquid supply to the analyzer.

It is characteristic of both forms of the invention that the hot mixture of refrigerant and absorbent vapor supplied to the rectifying and heat exchange elements R and R' flow in counter-flow relationship and in heat exchange relationship with the relatively cold solution which is supplied to the heat exchange and rectifying elements R and R' from the low temperature evaporator. By reason of this relationship the liquid supplied to the low temperature evaporator is cool, the overflow liquid flowing to the analyzer is at an elevated temperature and the vapors passing to the condenser leave the rectifying and heat exchange elements in direct heat exchange relationship with the freshly generated vapors.

It is also a characteristic of the present invention that since refrigerant for one evaporator is vaporized in a first heating zone, is condensed in a first condensation zone, is reevaporated in a second heating zone and is re-condensed in a second condensation zone during which process it is completely relieved of non-condensable gases

and of absorption liquid and vapor of absorption liquid.

It is therefore characteristic of the present invention that the low temperature freezing evaporator is supplied with substantially pure liquid refrigerant without, however, occasioning any loss of heat from the system by way of rectification. It is also characteristic that the rectifying process may economically be carried to absolute completion in the present construction as distinguished from partial completion in prior constructions.

While only one embodiment of the invention has been shown and described herein, it is apparent that various changes may be made in the arrangement and construction of parts without departing from the spirit of the invention or the scope of the annexed claims.

I claim:

1. Refrigerating apparatus comprising a pair of evaporators, a boiler, an absorber, means connecting said absorber and said evaporators for circulation of an inert gas therebetween, means connecting said boiler and said absorber for circulation of absorption solution therebetween, a heat exchange element arranged to receive vapors from said boiler and to supply condensate produced by liquefying said vapors to one of said evaporators, means for conveying condensate which has traversed said one evaporator to said heat exchange element, and means for condensing vapors evolved in said heat exchange element from condensate which has traversed said one evaporator and for supplying the condensate produced by liquefying said last mentioned vapors to said other evaporator.

2. Refrigerating apparatus comprising a pair of evaporators, a boiler, an absorber, means connecting said absorber and said evaporators for circulation of an inert gas therebetween, means connecting said boiler and said absorber for circulation of absorption solution therebetween, a heat exchange element having first and second passes, means to conduct vapors to the first pass 40 of said element from said boiler and to conduct condensate from said first pass to one of said evaporators, means to conduct condensate from said one evaporator to the second pass of said element, means for condensing vapors liberated from said condensate in the second pass of said element and for supplying the condensate produced in said means for condensing vapors to the other of said evaporators.

3. Absorption refrigerating apparatus comprising a pair of evaporators, a boiler, an absorber, means providing for circulation of absorption solution between said boiler and said absorber, means providing for circulation of inert gas between said absorber and said evaporators, and structure constructed and arranged to supply liquid to one of said evaporators derived by liquefying vapor evolved in said boiler and to supply liquid to the other of said evaporators derived by liquefying vapor evolved from liquid removed from said one evaporator.

4. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed 70 and arranged to liquefy vapor received from said

boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, and means for conducting liquid from said condenser to the other of said evaporators.

5. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, means for conducting liquid from said condenser to the other of said evaporators, an auxiliary condenser connected between said first part and said condenser to condense vapor uncondensed in said first part and to supply condensate to said first part.

6. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, means for conducting liquid from said condenser to the other of said evaporators, and means for conducting liquid from said second part to said boiler and for passing said liquid into heat exchange relationship with vapor produced in said boiler.

7. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one

10 evaporator by heat transferred from said first part, means for conducting vapor from said second part to said condenser, means for conducting liquid from said condenser to the other of said evaporators, means for conducting liquid from said second part to said boiler and for passing said liquid into heat exchange relationship with vapor produced in said boiler, an auxiliary condenser connected between said first part and said condenser to condense vapor uncondensed in said first part and to supply condensate to said first part.

8. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, means for conducting liquid from said condenser to the other of said evaporators, and means for passing liquid from said second part and liquid enroute from said absorber to said boiler in contact with vapor flowing from said boiler.

9. In a refrigerator a cabinet structure including an insulated refrigerating compartment and a vertically extending cooling air flue, insulated means dividing said refrigerating compartment into freezing and food preserving portion; an absorption refrigerating apparatus associated with said cabinet structure including an evaporator in each of said portions of said cabinet structure, 40 an air cooled condenser in said flue, an absorber, a boiler, means providing for circulation of absorption solution between said absorber and said boiler, means providing for circulation of inert gas between said absorber and said evaporators, 45 a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, and means for conducting liquid from said condenser to the other of said evaporators.

60 10. In a refrigerator a cabinet structure including an insulated refrigerating compartment and a vertically extending cooling air flue, insulated means dividing said refrigerating compartment into freezing and food preserving portions; an absorption refrigerating apparatus associated with said cabinet structure including heat rejecting means arranged to be cooled by air flowing through said flue, a boiler, means constructed and arranged to supply the evaporator in said food preserving portion of said cabinet

with a refrigerant produced by condensation of vapor produced in said boiler, means constructed and arranged to supply the evaporator in said freezing portion with refrigerant condensed from vapors evolved by absorption of the heat of condensation of the liquid supplied to the evaporator in said food preserving portion.

11. That improvement in the art of refrigeration which includes the steps of applying heat to a solution of refrigerant in an absorbent to evolve vapor therefrom, liquefying said vapor by heat exchange with liquid discharged from an evaporating zone, supplying said liquefied vapor to said evaporating zone, evolving vapor from the liquid discharged from said evaporating zone by the heat absorbed in liquefying said first mentioned vapor, and liquefying said last mentioned vapor and supplying the resulting liquid to another evaporating zone.

12. That improvement in the art of refrigeration which includes the steps of applying heat to a solution of refrigerant in an absorbent to evolve vapor therefrom, liquefying said vapor by heat exchange with liquid discharged from an evaporating zone, supplying said liquefied vapor to said evaporating zone, evolving vapor from the liquid discharged from said evaporating zone by the heat absorbed in liquefying said first mentioned vapor, liquefying said last mentioned vapor and supplying the resulting liquid to another evaporating zone, and flowing an inert gaseous medium through said second mentioned evaporating zone and then through said first mentioned evaporating zone.

13. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, and means for conducting liquid from said condenser to the other of said evaporators in heat transfer relationship with said one evaporator.

14. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, and means for

conducting liquid from said condenser to the other of said evaporators, said means providing for circulation of inert gas being so arranged that inert gas flows from said absorber to said another evaporator and then to said one evaporator.

15. In a refrigerator a cabinet structure including an insulated refrigerating compartment and a vertically extending cooling air flue, insulated means dividing said refrigerating compartment into freezing and food preserving portions; an absorption refrigerating apparatus associated with said cabinet structure including an evaporator in each of said portions of said cabinet structure, an air cooled condenser in said flue, an absorber, a boiler, the evaporator in said food preserving portion comprising an elongated gas and liquid passageway forming means provided with an extensive air cooling surface, the evaporator in said freezing portions comprising an elongated gas and liquid passageway forming means adapted to underlie and refrigerate freezing receptacles and the like, means arranged to receive vapor from said boiler and to condense such vapor by heat exchange with liquid discharged from said evaporator in said food preserving portion, means for conducting liquid condensed from said vapor from said vapor receiving means to said evaporator in said food preserving portion, means for liquefying vapor evolved in said vapor receiving means from the liquid discharged from said evaporator in said food preserving portion, and means for conveying liquid from said last mentioned liquefying means to said evaporator in said freezing portion in heat exchange relationship with the evaporator in said food preserving portion.

16. In a refrigerating apparatus, a pair of evaporators, a boiler, an absorber, a condenser, means providing for circulation of absorption solution between said absorber and said boiler, means providing for circulation of inert gas between said absorber and said evaporators, a heat exchange means including a first part and a second part, means for supplying vapor from said boiler to said first part, said first part being constructed and arranged to liquefy vapor received from said boiler by heat transferred to said second part, means for supplying liquid from said first part to one of said evaporators, means for supplying liquid from said one evaporator to said second part, said second part being constructed and arranged to vaporize liquid received from said one evaporator by heat transferred from said first part, means for conducting vapor from said second part to said condenser, and means for conducting liquid from said condenser to the other of said evaporators, said means providing for circulation of inert gas being so arranged that inert gas flows from said absorber to said another evaporator in heat exchange relationship with inert gas flowing from said another evaporator to said one evaporator.

17. Refrigerating apparatus comprising a pair of evaporators, a boiler, an absorber, means connecting said boiler and said evaporators for circulation of an inert gas therebetween, means connecting said boiler and said absorber for circulation of absorption solution therebetween, a heat exchange element arranged to receive vapors from said boiler, said element being positioned below one of said evaporators, a separation chamber positioned above said one evaporator and arranged to receive liquid from said heat exchange element produced by liquefying said vapors, means

for conveying liquid from said vessel to said one evaporator, means for conveying liquid which has traversed said one evaporator to said heat exchange element, and means for condensing vapors evolved from liquid which has traversed said one evaporator in said heat exchange element and for supplying the condensate to said other evaporator.

18. Refrigerating apparatus comprising a pair of evaporators, a boiler, an absorber, means connecting said boiler and said evaporators for circulation of an inert gas therebetween, means connecting said boiler and said absorber for circulation of absorption solution therebetween, a heat exchange element arranged to receive vapors from said boiler, said element being positioned below one of said evaporators, a separation chamber positioned above said one evaporator and arranged to receive liquid condensed from said vapors in said heat exchange element, means for conveying condensate from said vessel to said one evaporator, means including a condensing means for relieving said vessel of vapor discharging thereinto and for supplying said vessel with condensate from said vapor, means for conveying condensate which has traversed said one evaporator to said heat exchange element, and means for condensing vapors evolved from said last mentioned condensate in said heat exchange element and for supplying the resulting liquid to said other evaporator.

19. Refrigerating apparatus comprising a pair of evaporators, a boiler, an absorber, means connecting said boiler and said evaporators for circulation of an inert gas therebetween, means connecting said boiler and said absorber for circulation of absorption solution therebetween, power driven means for circulating inert gas through said inert gas circuit, a heat exchange element arranged to receive vapor from said boiler, gas lift pump means arranged to convey liquid condensed from said vapor from said heat exchange element to one of said evaporators, means for supplying pumping gas from said inert gas circuit to said gas lift pump means, means for conveying liquid which has traversed said one evaporator to said heat exchange element, and means for condensing vapors evolved in said heat exchange element from said liquid which has traversed said one evaporator and for supplying the condensate to said other evaporator.

20. Refrigerating apparatus comprising refrigerant vapor supply means, a first cooling unit, a heat transfer means, means for supplying vaporizable liquid which has traversed said first cooling unit to said heat transfer means, said heat transfer means being constructed and arranged to pass said refrigerant vapor in heat exchange relationship with a vaporizable liquid, means for supplying to said first cooling unit liquid produced by condensation of said refrigerant vapor in said heat transfer means, a second cooling unit, a condenser, means for conducting to said condenser vapor evolved from said vaporizable liquid, and means for conducting liquid from said condenser to said second cooling unit.

21. In a refrigerator a boiler, a plurality of evaporators, means for flowing liquid discharged from a first one of said evaporators in heat exchange relation with vapor produced in said boiler to liquefy said vapor, means for conducting said liquefied vapor to said first evaporator, means for condensing vapor liberated in said first mentioned means from said liquid discharging from said first evaporator, and means for conducting said last mentioned vapor to a second evaporator.

22. In a refrigerator a cabinet structure having freezing and food preserving compartments, a boiler, an evaporator in said freezing compartment comprising an elongated conduit underlying and in heat exchange relation with a substantially horizontal receptacle support, an evaporator in said food preserving compartment comprising an elongated conduit arranged to cool the air in said compartment, means for flowing liquid discharged from said evaporator in said food preserving compartment in heat exchange relation with vapor produced in said boiler to liquefy said vapor, means for conducting said liquefied vapor to said evaporator in said food preserving compartment, means for condensing vapor liberated in said first mentioned means from said liquid discharging from said evaporator in said food preserving compartment, and means for conducting said last mentioned vapor to said evaporator in said freezing compartment.

23. In a refrigerator a cabinet structure including insulated freezing and food preserving chambers, an evaporator having an extensive heat transfer area arranged to refrigerate said food preserving chamber, an elongated conduit arranged in said freezing chamber beneath a horizontal receptacle supporting plate, said conduit being inclined slightly to the horizontal to provide for gravity flow of refrigerant liquid therethrough, an elongated web providing a direct heat conducting path between said horizontal plate and said inclined conduit, a boiler, means for passing liquid discharged from said evaporator in said food preserving compartment in heat exchange relation with vapor from said boiler to condense said vapor, means for conducting said condensed vapor into said evaporator in said food preserving chamber, means for condensing vapor liberated in said heat exchange means from liquid discharged from said evaporator in said food preserving chamber, and means for supplying the condensate to said evaporator in said freezing chamber.

24. In a refrigerator a cabinet structure including insulated freezing and food preserving chambers, an evaporator having an extensive heat transfer area arranged to refrigerate said food preserving chamber, an elongated conduit arranged in said freezing chamber beneath a horizontal receptacle supporting plate, said conduit being inclined slightly to the horizontal to provide for gravity flow of refrigerant liquid therethrough, an elongated web providing a direct heat conducting path between said horizontal plate and said inclined conduit, a boiler, an absorber, means providing for circulation of an inert gas through said absorber and said evaporators in which inert gas which has traversed said evaporator in said freezing chamber flows through said evaporator in said food preserving chamber and thence to said absorber, means for passing liquid discharged from said evaporator in said food preserving compartment in heat exchange relation with vapor from said boiler to condense said vapor, means for conducting said condensed vapor into said evaporator in said food preserving chamber, means for condensing vapor liberated in said heat exchange means from liquid discharged from said evaporator in said food preserving chamber, and means for condensing said last mentioned vapor and for supplying the condensate to said evaporator in said freezing chamber.

25. In a refrigerating system that improvement which consists in liquefying vapor of a re-

frigerant and evolving vapor from a body of said refrigerant in liquid phase which has traversed a first place of evaporation by conducting said vapor and said liquid in heat exchange relationship with each other, evaporating said liquefied vapor in said first place of evaporation to produce a first refrigerating effect, passing vapor liberated from said body of refrigerant in liquid

phase in heat transfer relationship with a cooling medium to form another body of refrigerant in liquid phase, and evaporating said last mentioned body of refrigerant in liquid phase, and evaporating said last mentioned body of refrigerant in liquid phase in a second place of evaporation to produce a second refrigerating effect.
